SCRIBING FIXTURE

Edward Hochreiter, Cynwyd, Pa., assignor to
 Edward G. Budd Manufacturing Company,
 Philadelphia, Pa., a corporation of Pennsyl-
 vania

Application January 8, 1944, Serial No. 517,509

7 Claims. (Cl. 33—21)

1

The invention relates to a fixture adapted for inscribing the locations of trim lines or other markings on workpieces.

More particularly, the invention refers to a fixture for inscribing the trim lines on elongated profiles or sections which are curved in one or more planes.

Among the objects of the invention is a scrib-
 ing fixture which can easily and speedily be op-
 erated even by unskilled or semi-skilled persons,
 which insures very accurate marking of the trim
 lines, which permits the use of the forming dies
 for holding the articles to be inscribed, and which
 permits easy and speedy adjustment for differ-
 ent articles.

These and other objects of the invention are
 outstandingly achieved by a fixture provided with
 means for holding a support for the articles to
 be marked or inscribed and with one or more uni-
 versally adjustable guides for a scrib-
 ing tool.

The aforesaid and further features of the in-
 vention, as well as the advantages thereof, will
 be fully understood from the illustration of an
 embodiment in the attached drawings and from
 the following detailed description of same.

In the drawings:

Figure 1 is a side elevation of the new device
 at a substantially reduced scale;

Figure 2 is a plan view of the same device;

Figure 3 is a fragmentary plan view on a larger
 scale than Figure 2, showing in full lines the com-
 ponent parts in a middle position and in dot-
 and-dash lines certain parts angularly adjusted;

Figure 4 is an elevation on the scale of Figure 3
 partly in section along lines 4—4 and 4'—4', re-
 spectively, of Figure 3 with a die or form and a
 workpiece in place and with a scrib-
 ing tool in operation;

Figure 5 is a section along line 5—5 of Figure 3
 showing in full lines the middle position of the
 parts and in dotted and dot-and-dash lines, re-
 spectively, the tool guide proper in two different
 angularly adjusted positions;

Figure 6 is a section along line 6—6 of Figure 2
 on the scale of Figures 3 to 5 with a die or form
 and a workpiece in place;

Figure 7 is a fragmentary section along line
 7—7 of Figures 2 and 6 on a still larger scale; and

Figure 8 is a fragmentary perspective view of
 a form or die, of a workpiece thereon and of the
 lower end of a scrib-
 ing tool, on about the scale
 of Figures 4 and 6.

Supported on the floor 10 by a plurality of pairs
 of legs 11 are a pair of parallel beams 12 tied
 together by strips 12' carrying a long plate or

2

table 13. The latter may, for convenience of
 manufacture, shipping and storage, consist of
 several units joined together along lines 14.

Gibs 15 forming with the top of the table 13
 5 undercut guideways 16 are removably secured by
 bolts 17 to the long margins of the table. Along
 the center line of the table is secured a rack 18.

Two bridge-like structures 19 rest by means of
 10 legs 20 and feet 21 on the table 13. The feet 21
 extend into the passageways 16. A bracket 22
 forming an integral part of the structure 19 and
 screws 23 serve for firmly and immovably holding
 a die or checking form 24.

Each foot 21 has screwed therein a bolt 25
 15 which engages a plate or washer 26 guided in a
 downwardly open recess of the foot. The plates
 26 enter shallow grooves 27 extending parallel to
 the rack 18 and the passageway 16. Upon loos-
 20ening the screws 25, the structures 19 may be
 moved along the table to any desired position
 and there secured in place by tightening the
 screws so that the structures 19 are held by fric-
 tional engagement of the plates 26 with the bot-
 tom walls of the grooves 27 and of the feet 21 with
 25 the upper walls of the passageways 16.

Four further bridge structures 28 of a differ-
 ent design are located on the table 13. The num-
 ber of structures 28 depends upon the number of
 lines to be inscribed on a given workpiece.

30 Each structure 28 comprises a top plate 29, legs
 30 and feet 31. The feet 31 are supported on and
 guided by the table 13 and the passageways 16
 and are provided with screws 25 and pressure
 35 plates extending into the grooves 27 substantially
 identical with the screws 25 and plates 26 de-
 scribed in connection with the structures 19.

A transversely extending shaft 32 is rotatably
 supported in one of the legs 30 of each structure
 28 and in bearings 33 connected with the under-
 40 side of the top plate 29. One end of the shaft 32
 extends beyond one of the lateral margins of the
 table 13 and carries a hand wheel 34. A pinion
 35 is secured to the shaft 32 between the two
 bearings 33 and is in mesh with the rack 18.
 45 When the screws 25 are loosened, the structure 28
 can be moved along the table exactly to any de-
 sired position by turning the hand wheel 34.
 Thereafter, it may be secured in place by again
 tightening the screws 25.

50 Each bridge structure 28 carries a frame struc-
 ture 36 consisting of a bottom plate 37, two up-
 rights 38 and a top member 39. The bottom
 plate 37 rests on top of the plate 29 of the struc-
 ture 28 and engages a central hole of the latter
 55 by means of a vertical pin 40 so as to allow ro-

tation about the axis of said pin. The plate 37 is provided with two arc-shaped slots 41 extending concentrically to the pin 40. A screw bolt 42 has its shank extending through each slot 41, is screwed into one of a plurality of holes 43 provided in the plate 29 and has its head in engagement with the top of the plate 37. The pin 40, the slots 41 and the screws 42 permit the rotation of the structure 36 relative to the structure 28 and, consequently, relative to the longitudinal direction of the table 13, to any desired angular position and the securing in such position. Several such positions are shown in Figures 1 and 2 of the drawings and two positions are indicated in Figure 3 by full lines and dot-and-dash lines, respectively.

One shoe 44 is slidable on each of the uprights 38. The shoes 44 have their outer ends vertically slotted so that they can be firmly clamped against the respective upright 38 by means of a transversely extending bolt and nut 45. The inner ends of the shoes 44 are horizontally slotted at 46 and provided with a horizontal boring 47. Supported in each boring 47 is a pin 48 which is immovably held in place upon clamping the ends of the shoe 44 separated by the slot 46 together by means of the nut 49' screwed on the bolt 49, which latter is held in the shoe by the pin 50.

The pins 48 are rigidly secured by means of a screw or dowel 51 each to the ends 52 of a U-shaped member 53. Except for the ends 52, the member 53 is slotted at 54. The juxtaposed walls of the slot are exactly parallel and the slot has an exact predetermined width.

It will by now be understood that the slot 54 of each member 53 can be brought into any desired longitudinal and angular position relative to the table 13 by moving the structure 28 along the table, by turning the structure 36 relative to the structure 28 about the vertical axis of pin 40, by raising or lowering the member 53 with its shoes 44 along the uprights 38, and by swinging the member 53 with its pins 48 in the shoes 44 about the horizontal axis of the pins.

The form or fixture 24 has its upper marginal portion 55 shaped exactly to the contour of the workpiece 56 to be marked or inscribed. Marked on the form 55 by the lines 57, 58 (Figure 8) are the locations and the directions of the trim lines 57', 58' to be inscribed on the workpiece.

The form or fixture 24 may be the forming die which had been used for stretch-forming the article to be inscribed. Such forming may, for instance, be carried out by the methods and means disclosed in applicant's application for Letters Patent "Means for and method of forming articles," Serial No. 514,573, filed December 16, 1943.

The operation of the new device is as follows: At first, the form 24 is secured in place on the table 13 by means of the structures 19 and the screw 23 thereon. Hereupon, the structures 28 are moved along the table 13 to the location of the marking lines, such as the lines 57 and 58, on the form 24, and the structures 36 and members 53 are so adjusted as to angular position and height that the slots 54 in the members 53 have one wall each exactly coplanar with the respective line.

The exact adjustment is aided by the use of the scribing tool 59, the shank of which fits slidingly but practically without play into the slot 54. One end of the tool 59 has a sharp point at 60, whereas the other end is provided with a handle 61. One of the side surfaces of the tool 59 is

plane throughout the length of the tool, that is, to the point 60 (see Figure 8). It is this plane side of the tool 59 which slides on the wall of slot 54 coplanar with the respective marking line on the form 24.

After this adjustment, one workpiece 56 after the other is placed on the form or fixture 24 and the tool or tools 59 are moved in the respective slots 54 of the members 53 so that the trim lines, such as 57', 58' (Figure 8), are inscribed on the workpiece 56 at the exact location of the corresponding lines, such as 57, 58, on the form 24.

It will be understood that two or more workmen may operate the machine so as to speed up production. There may be one workman for each line to be inscribed on a specific workpiece.

The change-over from one form or fixture to another can easily and speedily be carried out by simply securing the new form on the structures 19 and by adjusting the members 53 in the same manner as just described.

The invention is not restricted to the details of the illustrated and described embodiment, but all modifications based on the principles and the spirit of the invention are intended to be covered by the attached claims.

What is claimed is:

1. A device for marking trim lines on articles comprising: a table; a structure; means on said table and said structure for guiding the latter on the former along a substantially straight path; means for holding a workpiece on said table; and means angularly adjustable on said structure for guiding a scribing tool across the workpiece and arranged to leave a free space for a three-dimensional workpiece between it and the table.

2. In a device of the class described: a base; a structure; means on said base and said structure adapted to support and guide the latter on the former along a substantially straight path; means adapted to hold a workpiece fixedly relative to said table; a second structure supported on said first structure rotatably about an axis extending substantially vertically to said path; guiding means for a tool supported angularly adjustably about an axis extending generally transversely to said first-named axis and to the said path.

3. In a device according to claim 2, means adapted for adjusting the perpendicular distance of said tool guiding means from said base.

4. In a device of the type described: a base; a structure; means for guiding said structure on said base along a predetermined path and securing it at any desired location of said path; a second structure supported by said first structure angularly adjustable about an axis extending about perpendicularly to said path and means for securing said two structures together in any desired angular position: said second structure comprising at least one member extending in the general direction of said axis and away from said first structure and said base; guiding means for a tool; and means for holding said guiding means on said member adjustably along the length of the latter and also angularly adjustable about an axis extending transversely to the first-named axis.

5. In a device of the type described: a base; means for holding a workpiece in predetermined position on said base; a plurality of structures provided with means for guiding a scribing tool; means on said base and said structures for guiding each one of the latter individually on the former and for securing them in different posi-

2,402,890

5

tions along a predetermined path; the device permitting the inscription of a plurality of marking lines in the exact desired spacing and angular position on one workpiece after the other.

6. In a device of the type described: a base; at least one structure provided with means for guiding a scribing tool; guiding means on said base for said structure; and further means guided by said last-named guiding means adapted to support means for holding workpieces in a predetermined position.

6

7. In a scribing fixture: an adjustably supported member; a slot with parallel walls in said member; a scribing tool having a pair of parallel surfaces fitting between and slidably guided by said walls of said slot; one of said parallel surfaces of said tool extending unbrokenly to the point of the tool so that one of the walls of said slot is coplanar with the line drawn by the tool when moved along the slot.
